UNITED STATES PATENT OFFICE.

BRUNO OTTO WAGNER, OF SWISSVALE, PENNSYLVANIA.

ELECTROMAGNETIC SWITCH-SETTING APPARATUS AND ELECTRIC RAIL-HEATER.

No. 809,236.

Specification of Letters Patent.

Patented Jan. 2, 1906.

Application filed March 9, 1905. Serial No. 249,315.

To all whom it may concern:

Be it known that I, BRUNO OTTO WAGNER, at present residing at Swissvale, in the county of Allegheny and State of Pennsylvania, have invented certain new and useful Improvements in Electromagnetic Switch-Setting Apparatus and Electric Rail-Heaters, of which the following is a specification.

My present invention relates to certain new and useful improvements in electromagnetic switch-setting apparatus and rail-heaters, and the same is more particularly adapted for use in connection with my improved system of electric signaling and switch-setting for railroads disclosed in my copending application, filed October 28, 1904, Serial No. 230,521.

Primarily my invention seeks to provide means for moving rail-switches electromagnetically under the control of the operator, which also comprises means for closing branch circuits to operate indicating devices at the operator's station to indicate the position of the switch.

My invention also seeks to provide means for electrically heating switch-rails in the winter to prevent them becoming clogged with snow and ice, and thereby rendered ineffective.

In its generic nature my improved switch-setting apparatus comprises a hermetically-sealed casing in which is mounted a reciprocating electric motor of a peculiar type, a longitudinally-movable rod coöperatively joined with the armature of said motor and to the switch-point-connecting rod, and means coöperating with said longitudinally-movable rod for holding the same in its adjusted positions. My invention also includes a pair of circuit-closers operable by the reciprocating armature for closing supplemental indicating or signaling circuits to indicate to the operator that the switch has been properly set.

In its generic nature my improved rail-heater comprises a casing adapted to be secured to the under side of the rail-switch base-plate, in which casing is mounted a plurality of heating-coils embedded in suitable material.

In its more detailed nature my improved switch-setting apparatus includes stationary solenoid and pole pieces of special construction semi-inclosed by a metallic housing, an iron armature with two magnet-coils which when energized cause the armature to de-

scribe a single motion in one direction or the other, depending upon the direction in which current is flowing in the magnet-coils, and a combination of members for transmitting this motion elastically to the switch-shifting rod, including a toggle-spring attachment for mechanically locking the rail-points to their adjusted positions and a pair of contact-making devices actuated by the impulse of the armature as it reaches the limit of its movement in both directions.

With other objects in view that have been hereinbefore mentioned the invention also includes certain novel construction, combination, and arrangement of parts, all of which will be first described in detail and then specifically pointed out in the appended claims, reference being had to the accompanying drawings, in which—

Figure 1 is a longitudinal section of the rail-switch-setting apparatus, taken substantially on the line 1 1 of Fig. 2. Fig. 2 is a cross-section on the line 2 2 of Fig. 1, taken in the direction of the arrow. Fig. 3 is a detail view of the shifting-rod, together with its toggle-spring attachment. Fig. 4 is a detail view of the toggle-spring attachment looking in the direction of the arrow in Fig. 3. Fig. 5 is a detail sectional view on the line Z Z of Fig. 1. Fig. 6 is a similar view on the line 6 6 of Fig. 5, showing the manner of fastening the driving-stud to the armature-body. Fig. 7 is a detail view of the flexible cable-leads and their connection to the armature-coil. Fig. 8 is a cross-section on the line 8 8 of Fig. 7. Fig. 9 is a top plan view of the circuit-closing device, its operating-lever being removed. Fig. 10 is a central horizontal section of one of the rail-switch-heating boxes. Fig. 11 is a cross-section on the line 11 11 of Fig. 10. Fig. 12 is an end view of the heating-box with its cover removed. Fig. 13 is a plan view of the switch portion of the railroad-tracks and its immediate coöperating parts. Fig. 14 is a part section and part elevation on the line 14 14 of Fig. 13. Fig. 15 is a diagrammatic view illustrating a complete system, such as disclosed in my application hereinbefore referred to, in connection with which my present invention is particularly designed to operate. Fig. 16 is a detail view showing the stuffing-boxes for passing the leading-in cables into the housing 5.

Referring now to the accompanying drawings, in which like characters of reference des-

gnate like parts in all the figures, I designate the main track, which is connected with the side tracks II by a switch, as clearly shown in Figs. 13 and 14 of the drawings, by reference to which it will be seen that the switch-points 1^a 2^a are pivoted at 1^a 2^a, respectively, to steel plates 1^b 2^b, respectively, upon which they rest. The switch-points 1^a 2^a are connected to move in unison with the rod 38 of the electromagnetic switch-setting apparatus inclosed in the housing 5, which will be more fully referred to later. As conditions may require, a pit 7^a may be provided to receive the switch-point-connecting rod and the switch-setting mechanism; but when this is the case a suitable offtake 7 connects with the pit 7^a to draw off any water which may accumulate in the pit.

The semaphore-blade mechanism is preferably inclosed in a metallic casing 8, while the night-signal 16 is placed in a supplemental casing 9, adjoining the casing 8 and forming, as it were, an integral structure on the top of a suitable pole 10 when the semaphore form of signal is used.

When my invention is used in connection with "dwarf signals" of the ordinary type, in which the signal comprises two plates of different colors mounted axially on a short vertical shaft and at right angles to each other, so as to rotate with the shaft through an angle of ninety degrees, and in which a lantern of rectangular shape having different-colored windows is secured at the junction of said plates, so that when turned into its locked position it will throw a corresponding and steady color-signal in the distance, the construction is substantially the same as for the semaphore mechanism. The operating mechanism of the dwarf signal is placed in a weatherproof housing similar to that of the semaphore, as described.

When the switch-blades are in the position shown in Fig. 13, so that a train approaching from K in the direction of L will be switched over to the siding II, the semaphore-blade is held horizontally, as shown in Fig. 14, so as to indicate to trains approaching from L toward the direction of K that the switch has been set for the siding and that there is danger for a train to approach further.

Referring now more particularly to Fig. 15 of the drawings, which designates diagrammatically the complete arrangement of my improved system, it will be seen that the portion indicated below the parallel horizontal dot-and-dash lines constitutes the portion of my improved apparatus within the operator's station, which comprises the switch-indicator A, the signal-indicator B, the circuit-closing switch E, the reversing-circuit-closing switch F, the current-indicating ammeter 13, together with the electrical connections between each of said parts and their elec-

trical connections to the line-wires. The line-wires, six in number, which connect the operator's station with the track apparatus, are designated by the reference-letters M', M², M³, M⁴, M⁵, and M⁶, and these wires may be run either as air-lines, or they may be combined into one or more cables and run underground.

For convenience of description I shall first describe the general construction and arrangement of apparatus in the operator's station.

The track-indicator A comprises a soft-iron horseshoe-magnet 19, between the legs of which on a pivot 21 the armature 23 is mounted. The armature 23 is provided with an indicating-pointer 25 to coöperate with a suitable dial-plate upon which suitable indicating characters are formed—for instance, the characters I and II—to indicate that track I is clear or that siding II is open.

19^a and 19^b designate the coils of the magnet 19, one of which, 19^a, is connected with the line-wire M⁴ and to the contact-points f¹ and f³ of the reversing-switch F, while the other, 19^b, is connected to the line-wire M⁵ and to the contact-points f¹' and f² of the switch F.

The signal-indicator B is of similar construction to the track-indicator A and comprises generally a soft-iron horseshoe-magnet 20, provided with separate coils 20^a and 20^b, the coil 20^a being connected with the line-wire M' and the coil 20^b being connected to the line-wire M², while both coils 20^a and 20^b are also connected with the contact-point e of the switch. The magnet 20 is mounted on its panel in a vertical position similarly to magnet 19 of the indicator A, and midway between the legs of the magnet 20 I suspend on a pivot 22 an armature 24, which in its normal position is held equidistant from the pole-pieces of the magnet 20 and is provided with an indicator-pointer 26 to coöperate with a suitable dial upon which suitable indicating characters are formed—as, for instance, "C" and "D"—to designate "clear" and "danger," respectively. The indicator B not only indicates the position of the signals, but also indicates defects in the line. The indicator A not only indicates the position of the track-switch, but also defects in its respective line, as will be more fully understood hereinafter.

The switch F is in the nature of a double-throw reversing-switch, and it has its knife-contacts f⁴ and f⁵ connected with the line-wires M³ and M⁴, respectively. The contact-point e of the switch E and the contact-point f⁵ of the switch F are both connected with the line-wire M⁶ through a cut-out switch 12, as shown, and the contact-point e' of the switch E connects, through the ammeter 13, to the line-wire M³. The contact-points e² e³ of the switch E connects, through safety-fuses 14 130

and 15, respectively, with the negative and positive bus-bars, (not shown,) respectively, of the power-station.

The ammeter 13 may be of any approved construction, as the same *per se* forms no part of my present invention.

The semaphore mechanism H comprises a rotatable iron armature 55^a of the Siemens shuttle type, upon which the armature-coil 55^b is wound. The armature 55^a is secured to the semaphore-shaft, which is journaled in the front and rear walls of the housing 8 and to which the signaling-arm 3 and tail-plate 3^a of the semaphore are attached.

53^a and 53^b designate a pair of stationary field-magnet coils for coöperating with the armature 55^b, and these coils are connected in series to produce north and south polarity, (designated by N and S, respectively,) on opposite sides of the armature 55^a to coöperate with the magnetic poles x and y of the said armature. The coils 53^a and 53^b are connected in series with one another and across the line-wires M³ and M⁶ and in multiple with the field-coils 27^a and 27^b of the switch-setting mechanism G, hereinafter again referred to:

68^a 68^b designate a pair of circuit closers or keys, and the lever or movable contact portion of each circuit-closer 68^a 68^b are electrically connected together by a wire 83, which connects with a two-branch switch 17, one contact 17^a of which connects, through a signaling-lamp 16, with the line-wire M³, while the other contact 17^b of the snap-switch 17 connects, through a resistance-coil 18, to the line-wire M³. The circuit-closers 68^a and 68^b are normally held open by springs or other equivalent devices.

55ⁱ designates a lever fastened to but insulated from the armature 55^a, which when the armature moving the semaphore-blade reaches the limit of its movement engages one or the other of the movable contact or lever portions of the circuit-closers 68^a 68^b to cause it to close the circuit. The fixed contact of the circuit-closer 68^b is joined to the line-wire M', while the fixed contact of the other circuit-closer 68^a is connected to the line-wire M². To limit the angle of movement of the semaphore-blade and lock it to its final position to prevent it from turning backward when current is cut off from the apparatus, any suitable means (not shown) may be provided, as the same *per se* forms no part of my present invention covered by this application.

The snap-switch 17 is preferably mounted at any convenient place on the signal-pole 10, so that the same may be operated to cut out the lamp 16 and cut in the resistance 18, or vice versa, as conditions may require, it being understood that the ohmic resistance of the lamp 16 and that of the resistance 18 must be the same. The lamp 16 and resistance 18 are disposed within the casing 9, as before mentioned.

When the armature 55^a is in motion, the keys 68^a 68^b are both set free, and the circuit containing the lamp 16 is thereby opened. A protraction in this period or a failing of the contact-making devices would allow the lamp 16 to remain cut out, and thereby cause severe accidents to happen. To overcome this, I provide a second lamp 71, which is inclosed in a colored lantern 4 of the semaphore-casing, which lamp 71 I connect across the terminals of the armature-coil 55^b and in parallel with the armature-circuit 55^b, the lamp 71 being rated at a voltage equal to the difference of potential at the terminals of the armature-coil 55^b. A small resistance or re-

actance coil 82, connected in series with the lamp 71, serves to compensate the excessive voltage and flow of current at the moment of closing the armature-circuits, so as to protect the said lamp from injury—as, for example, supposing the semaphore-blade is in an inclined position (see Fig. 14) and the switch 12 is closed, so that the stationary field-coils 27^a 27^b of the switch apparatus G and those, 53^a 53^b, of the semaphore mechanism H are excited, the armature 55^a of the semaphore mechanism being in such a position with respect to the field-coils 53^a 53^b that the maximum number of lines of force are traversing the said armature in the direction of 53^b x y 53^a. Now when the lever of the reversing-switch F is thrown onto contacts f² f³ the armature of the rail-switch-setting apparatus moves from left to right and the semaphore-blade from its position 3^x to 3. Looking in the direction of the pole y of the armature 53^a, the current will flow clockwise in wire turns of the coil 55^b and produce a magnetic flux in the direction of y to x in the iron body of the armature, which flux, because it is opposite to the flux of the coils 53^a 53^b, weakens the active field of the magnetic circuit and causes the armature to rotate counter-clockwise. Decreasing the magnetic field results in exciting an electro-motive force which causes a clockwise current to flow in the coil-windings when looking in the direction of the magnetic flux through the armature, and thereby increases the electrical potential at the terminal in the armature 55^b. At the moment of closing the circuit by the switch F the lamp takes the electrical pressure at the armature-terminals, which will be equal to the drop in voltage in the armature-coil (due to its internal resistance) plus the inductive electromotive force, whose strength depends on the number of wire turns which weaken the active field of the magnetic circuit and the time in which the change is brought about. The coils of the armature 29 of the switch-setting apparatus G will cause no inductive reaction in the armature, as said coils are wound in opposite directions to each other.

Supposing the number of turns in the ar-

mature-coil to equal eight hundred, the number of lines of force produced in this coil by a working current of 4.4 amperes in this branch to equal forty thousand centimeter gram seconds units, the time of changing the flux by this amount assumed to be one-fifteenth seconds, copper resistance of armature-coil to equal nine ohms, then the effective voltage at the lamp-terminals at the moment the armature-voltage is closed will be 44.4 volts. In this case an incandescent lamp rated at forty volts would be used, because 39.6 volts is the electrical pressure at the armature-terminal after the inductive action of the coil has ceased, and in view of the fact that excessive voltage shortens the life of a lamp, particularly when the lamp is cut in and out many times a day, a small reactance-coil 82 is connected in circuit with the lamp 71 to absorb the eleven per cent. of excessive voltage at the moment of closing the armature-circuit.

The rail-switch-setting apparatus (designated generally by G in Fig. 15 of the drawings) comprises the magnet-coils 27^a 27^b, of insulated copper wire, which coils are located in cup-shaped iron shells 27^c 27^d, respectively. The shells 27^c 27^d are held in a fixed and oppositely-disposed position to each other inside of a housing of non-magnetic material which is fastened to the iron shells 27^c 27^d by a plurality of screws 28, (see Figs. 1 and 2,) and the housing consists of two semicircular portions, (designated by 28^a and 28^b,) the part 28^a serving as a top portion, while the part 28^b serves as a base portion. The top and base portions 28^a and 28^b, respectively, are so arranged with respect to the shells 27^c and 27^d as to leave two side openings (designated by w' and w², see Fig. 2) extending the entire length of the housing. The base 28 is provided with legs by means of which it is fastened to the bottom plate 5^a of the housing 5, which incloses the entire switch-setting apparatus, while the top part 28^a on one side carries a horizontally-projecting hub or boss 28^c, the purpose of which will presently appear. Both shells 27^c and 27^d are of like construction, each consisting of a hub-shaped portion 27^e, provided with a central aperture, a short tubular portion 27^f, provided on the outside with a peripheral collar 27^g, to which the housing parts 28^a and 28^b are secured by the screws 28, before mentioned. Each shell 27^c and 27^d also includes an outer web for connecting the hub 27^e with the tubular portion 27^f.

Mounted to slide in the central apertures of the shells 27^c and 27^d is a sliding iron rod 29, to which the iron body of the pulley-shaped armature 30 is secured. The pulley-shaped armature 30, like the shells 27^c and 27^d, is cast in one piece and comprises a hub 30^a, a web-shaped portion 30^b, and a rim 30^c. The armature-body 30 is formed with two end cavities to receive the armature-coils 31^a 31^b, re-

spectively, of insulated copper wire, which are wound in opposite directions and connected in series to each other, so that like magnetic polarities will be produced in both outer ends of the armature-rim 30^c when a current is sent through the coils. The armature-rim 30^c is provided with internal conical faces at both ends to fit the external conical end faces of the tubular portion 27^f of the shells 27^c and 27^d. To maintain the armature-coils 31^a 31^b in their proper positions, two disks 32^a 32^b, respectively, of non-magnetic material are secured to the ends of the hub 30^a by screws, as clearly shown in Figs. 1, 7, and 8.

The magnet-coils 27^a and 27^b are secured in position on the hub portions 27^e of the shells 27^c and 27^d, respectively, by disks 32^c and 32^d, respectively, while the wire terminals of said coils are carried through insulated bushings 27^g, 27^h, 27ⁱ, and 27^k, respectively. (See Figs. 1, 2, and 7.)

As will be seen with reference to Figs. 7 and 8, the armature-rim 30^c is provided with a channel or groove 30^f and two slots 30^d and 30^e within said channel, all being arranged parallel with the shaft 29. Within said groove or channel 31^f and fastened to the armature-body is a prismatic block 31^g of insulating material—such as hard fiber, lava, slate, or other similar substance—said block 31^g being arranged to slide lengthwise in the opening w' of the housing 28^a 28^b and being provided with four apertures to support insulated flexible cables which are joined to the armature-coils. Two short cable-leads serve to connect both armature-coils with each other, while the cables 31^c and 31^d are adapted to connect with the terminal plate 31^f on the flat portion 5^e of the housing-frame 5^b, as clearly shown in Fig. 2 of the drawings. The terminal plate 31^f consists of an insulating base-plate of slate, marble, or lava, on which a plurality of metallic terminal blocks are mounted, preferably eight (8) terminals, four of which are provided with three binding-screws each, while the others are provided with two screws only.

Diametrically opposite to the cable-block 31^g and arranged in the channel 30^h of the armature-rim 30^c is a metallic block 34, fastened to the armature-rim by cap-screws 34^a and 34^b, as shown, and the said block 34 is guided in the opening w² of the solenoid-housing, as clearly shown in Figs. 1, 2, and 5 of the drawings. The middle portion of this block is provided with an integrally-formed hub to receive the projecting steel bolt 33, which is firmly secured to it, and transmits the motion of the armature to an intermediate lever 35, (see Figs. 1 and 5,) and the said lever 35 has its fulcrum upon the bolt 36 at the boss 28^c, (see Fig. 5,) whose boss is formed on the housing portion 28^a. The lower arm of the lever 35 is formed with a claw 35^a, which em-

braces the bolt 33, while the upper end of the arm 35 is formed with a bifurcated jaw 35^b to surround the metallic sleeve 37 and engage with the cross-pin 37^a by means of slots in both arms and jaw 35^b. To obtain the advantage of a long intermediate lever 35, the pin 37^a is located in the upper portion of the sleeve 37, where it is securely held in a fixed position by the set-screw 37^b.

10 The sleeve 37 is slideable upon an iron or steel rod 38, upon which rod 38 and on each side of the sleeve 37 coil-springs 37^c 37^d are arranged.

15 40^a 40^c designate adjusting-nuts on the rod 38 for coöperating with the coil-springs 37^c 37^d, respectively. (See Figs. 1 and 3.)

Two counter-nuts 40^b and 40^d serve to secure the adjusting-nuts in their respective positions. The ends 38^a and 38^b of the rod

20 38 are smaller in diameter than the collar portion and are endwise-movably mounted in bearings 39^a 39^b, respectively, which are formed in the shape of "stoppers" and fit into similar openings in the short side walls

25 in the housing-frame 5^b, to which they are secured by cap-screws. To facilitate taking the mechanism to pieces, these two openings are large enough to enable the sleeve 37 to be passed therethrough with ample clearance-

30 space. As shown more particularly in Figs. 1 and 3, the screw-threaded portion 38^c of the rod 38 carries, in addition to the above-mentioned nuts, a coupling-piece 41 for coöperating with a toggle-spring attachment, and

35 35 the said coupling-piece consists of a cylindrical sleeve and a pair of clevises 41^a, all formed of a single piece of cast-iron or other suitable metal. Hinged in the clevises 41^a on a pin 41^b is an iron eyebolt 42, which is

40 guided by and slideable in apertures in the arms 43^a 43^b of a swinging bracket 43. The bracket-arm 43^b is formed with a bearing 43^c and is so arranged as to be capable of turning upon the pivot 44^a of a steel stud 44, which is

45 tightly secured into a boss 5^d of the housing-frame 5^b, as shown in Fig. 2. To the eyebolt 42 a collar 42^a is fastened by means of a pin 42^b, and a coil-spring 45 is fitted on the bolt 42 between the arm 43^b and the collar 42^a.

50 By reason of the arrangement of the rod 42, its collar 42^a, the spring 45, and the bracket 43, in which they are mounted, the swing-bracket 43 tends to always assume an inclined position to the shifting-rod 38, and thereby

55 lock the latter to its final positions of movement. The springs 37^c and 37^d on the rod 38 serve as buffers to take up the percussion of the toggle-spring attachment.

To join the shifting-rod 38 to the connecting-bar 6, (see Figs. 13 and 14 of the drawings,) a metallic coupling-piece 46 is secured to the end 38^b of the rod 38 by a pin or key

60 46^a, as shown in Figs. 1 and 3. The protecting metallic housing 5 consists of a bottom

65 plate 5^a, a frame 5^b, and a cover 5^c, all of

which parts are preferably constructed of cast-iron. The bottom plate 5^a and the cover 5^c are shown in Figs. 1 and 2 of the drawings as being secured to the frame 5^b by a number of cap-screws, and I desire it under-

70

stood that I may cast the frame and bottom plate in a single piece, if found desirable, and hinge the top plate 5^c to the frame 5^b to operate as a trap-door with hinges and lock in

75

any ordinary manner, and thereby avoid the use of screws to secure the parts of the casing together. In either case, however, the cover-plate is provided with one or two eyebolts 5^f

5^g to facilitate lifting the frame. The frame 5^b, as before intimated, has two openings and 80 bosses for the aforesaid bearings 39^a 39^b and a boss 5^d for the toggle-bracket support as well as a flat portion 5^e for the terminal plate.

In practice the casing 5 is provided with metallic stuffing-boxes (see Fig. 16) for the lead- 85

ing-in cables which are similar in construction to those of the heating-boxes. (Shown in Figs. 10 and 11 of the drawings.) In practice there are six of these stuffing-boxes for the casing 5, four of which are designed to per-

90

mit passage of a three-wire cable, while the other two are for one-wire cables, to allow connection with the heating-boxes. By providing these stuffing-boxes for the entry of the cables all connections can be made within 95

the housing 5, and the use of a hermetically- closed separate junction-box is avoided.

The circuit-closers or keys 47^a and 47^b are each mounted upon a plate 48, of slate, marble, lava, or other suitable insulating and non-combustible material, which plates 48 are secured by countersunk screws 48^a and 48^b to the bottom plate 5^a of the housing 5. (See Figs. 1, 2, and 9.) Each circuit-closer

100

consists of a metallic pillar 49, that rises from a foot-plate 49^a and terminates in a horizontal arm and jib 49^c with an adjoining hub portion 49^d. An angular lever 50 is fulcrumed upon the cylindrical neck of a screw 49^e,

which is fastened into a boss 49^b at the place 105 where the aforesaid arm joins the pillar. 51

designates a metallic plate having a mercury-containing cup 51^a. The pillar 49, as well as the terminal plate 51, is secured to the insulating base-plate 48 by screws whose heads 110

are deeply sunk into the bottom of the base-plate, while the threaded portion of the screws are screwed into the foot-plates 49^a 51^a, respectively, and the extending ends of said screws being provided with nuts for making 115

wire connections.

The vertical arm of the lever 50 is formed into a head-piece that carries an adjustable set-screw 50^a and is centrally slotted in a line parallel with the axes of the screw. The 120

pressure against the threads of the screw can be increased to secure the screw in place by means of a cap-screw 50^b, arranged above and at right angles to the screw 50^a. The end piece of the lower arm of the lever 50 is 125

130

130

arranged similarly to the end piece of the vertical arm of the lever 50 and is provided with a screw 50^d, serving the same function as the screw 50^b. A set-screw 50^c is so located that 5 its pointer end will dip into the mercury-cup 51^a and close the electric circuit when the lever 50 is actuated by the moving power of the armature. Instead of slitting the lever-heads and using separate tightening-screws 10 50^c 50^d, respectively, I desire it understood that I may provide both lever ends with plain hubs and use counter-nuts to tighten the aforesaid screws to their places. A coil-spring 52, attached to a pin 49^f on the pillar 15 49 and a pin 50^e on the lever 50, raises the latter until it engages the adjusting-screw 49^g, held in the hub-shaped end of the jib 49^e to lift the contact-screw 50^e from the mercury-cup.

20 As will be further seen by reference to Fig. 1, hard-fiber bolts 29^a 29^b, formed with slightly-projecting heads, are screwed into the ends of the armature-rod 29, and these bolts serve to insulate the armature or circuit-closers to prevent the armature 29 becoming charged with current when in contact with the circuit-closers

Considering now the rail-heaters, (disclosed in detail in Figs. 10, 11, and 12,) it will be seen 30 that each rail-heater comprises a plurality of porcelain, clay, or lava tubes 72^a, 72^b, and 72^c, provided with helical grooves over its cylindrical surfaces, and these tubes are held by friction on iron tubes 73^a, 73^b, and 73^c, 35 which are fastened to a cast-iron plate 74, forming, as it were, a partition-wall within the cast-iron casing 75, which casing incloses the heaters entirely and protects them against moisture and other injuries. A number of 40 cap-screws 74^a serve to fasten the plate 74 against a ledge 75^a inside of the casing 75, the open end of which casing is covered by a metallic plate 76, hermetically pressed against the casing by cap-screws held in the projecting portions 75^b and 75^c of the casing 75. The cover-plate 76 is provided with two stuffing-boxes by means of which the conductor-cables are hermetically carried into the interior of the casing to connect with the 45 aforesaid heating-coils. Each stuffing-box consists of a metallic cap 77, internally threaded to fit the neck portions 76^a 76^b, respectively. A soft-lead or rubber ring 78 serves to produce a hermetical joint between the cable and the stuffing-box. In order to 50 connect the cable with the resistance-wire (heating-coil) that is wound in the helical grooves on each porcelain tube, the uninsulated portion of the conductor of said cable 55 is carried through heat with standing and insulating bushings 79^a, 79^b, 79^c, and 79^d inside of the metallic tubes 73^a 73^b 73^c. All joints are then made tight by means of screws on the metallic clamping-rings 80^a, 80^b, 80^c, 80^d, 80^e, 60 80^f, and 80^g, which latter are held by friction

and set-screws at both ends of each insulating-tube 72^a, 72^b, and 72^c. The space between the heating-tubes and the casing-wall is filled with sand, and the boxes are fastened on the under side of the base-plates of the 70 rail-switches by means of cap-screws passing through the lugs 75^d, 75^e, 75^f, and 75^g. The rail-heaters 11^a and 11^b just described are preferably connected in series in the main line-wire M³ between the switch-setting apparatus G and the operator's station. 75

Having thus generally described the circuits and operative arrangement of the parts constituting my present invention and the complete system in which it is particularly 80 adapted for use, I shall now briefly proceed to explain the consecutive steps of operation of my present invention as used in connection with the complete system before referred to.

85 Operation: Assuming that a night train is expected to come over track L in the direction from L to K and the position of the rail-switch and semaphore-blade being as shown in Figs. 13 and 14, as the track I is still broken 90 by the switch-points 1 2 (being set to direct a train into the siding) the signal-arm 3 of the semaphore stands in a horizontal position and the colored-glass disk in the tail-plate 3^a, which plate is in conjunction with the signaling-arm 3, covers the rear opening in the casing 9, thereby throwing a colored-light signal in the direction toward L to warn the engineer of an approaching train that there is danger. The armature 29 of the switch apparatus G is now in the position shown in Fig. 15, whereby the circuit-closer 47^b is closing a branch circuit from the double pole-switch F through the coil 19^b, line-wire M⁵, circuit-closer 47^b, resistance 81, wire 81^a, 95 field-coil 27^b, main return-wire M⁶, back through switch E to current source. At the same time an additional current from switch F passes through coil 19^b of the indicator A and line-wire M³, through coils 31^b 31^a of armature 29 and wire M⁴ to the terminal block of the semaphore-armature, where it is split into two branches, one part of the current passing through armature-windings 55^b, the other part passing through light 100 71 and reactance-coil 82, so that the sum of both currents will flow through wire M⁵, armature-coils 31^b 31^a of the switch-setting apparatus, armature-coil 55^b of semaphore apparatus, line-wire M⁴, coil 19^a of indicator A, to the other pole f³ of the reversing-switch F, to the main return-wire M⁶. It is obvious that under these conditions the coil 19^b is producing a stronger magnetic pull 105 toward the armature 23 than the coil 19^a, and therefore the armature 23 is moved in the direction shown in Fig. 15 to direct its pointer 25 over the indicating character II to signify that side track II is free for passage while track I is broken. Another cur- 110

130

rent is passing at the same time through the main wire M^3 and the electrical heaters 11^a 11^b to a main terminal plate inside of the housing 5 of the switch-setting apparatus G, 5 where it is divided into two branch circuits, one portion of the current passing through the field-coils 27^a 27^b and the other portion through the line-wire M^{3x} to the semaphore apparatus in the semaphore-housing 8, 10 where the current again divides, as follows: one portion passing through the lamp 16 to the contact 17^a and across switch 17 through wire 83 to the circuit-closer 68^a, which being closed permits the current to flow through 15 line-wire M^2 and coil 20^b of the indicator B to contact e of the switch E, across the switch-blade to contact e^2 , and through fuse 14 to the negative bus-bar of the power-station. Another portion of the current passes 20 through the field-coils 53^b 53^a of the semaphore-operating mechanism to the line-wire M^6 and through the line-wire M^6 and switch E to the negative bus-bar of the power-station. When, however, the switch 17 is 25 turned to close with the contact 17^b , the portion of the current which was flowing through lamp 16 will then flow through resistance 18 and the lamp 71 will be cut out. As the current flows through the coil 20^b the armature 30 24 will be attracted toward the right until its indicator 26 points to the dial-letter "D" to indicate that the semaphore-blade is in its horizontal position, to which it has just been moved, it being understood that the toggle 35 devices connected with the armature of the semaphore-operating mechanism, together with the action of the magnetic fields of the armature-coil 55^b and the field-coils 53^a and 53^b, sustain the semaphore-blade in its set 40 position. In the switch-setting apparatus G a magnetic field of constant polarity is produced by its two field-coils, so that, for instance, the inside end of the coil 27^a forms a south pole and that of the coil 27^b a north 45 pole. In order to force the armature 29 into the right-handed position, as shown in Fig. 15, the outer ends had to be rendered with south magnetic poles, which was done by throwing the lever of the reversing-switch F 50 into position shown in Fig. 13 to engage with the contacts f^2 f^3 . When the switch 12 is open, the current-flow through coils 27^b, 53^a, and 53^b is reduced to a minimum, while a slightly-stronger current from the line-wire 55 M^3 through the heaters 11^a 11^b is passing the field-coil 27^a, wire 81^a, resistance 81, then joining with the main branch flow in the armature-windings 31^b, 31^a, and 51^b, line-wire M^4 , and indicator-coil 19^a, &c., to slightly 60 increase the attractive power of that pole of the indicator-magnet 19 which lies above the dial-letter "I." The armature 23, however, will not change its position over the dial-letter "II," since the same is practically out of 65 the sphere of the attractive power of said stronger magnet-pole. Neither will opening the switch 12 effect the functions and positions of the other operating devices, so that no visible changes will be noticed in the whole system except in the reading of the 70 ammeter 13, which shows a reduced current consumption. After breaking the armature-circuit by lifting the lever of the switch F the armature 23 of the indicator A will drop to its peripheral position, whereas armature 29 of switch-setting apparatus and armature 55^a of semaphore mechanism are held in their set positions by any suitable toggle devices, (not shown,) and a small current 75 will pass through line M^3 , heaters 11^a 11^b , line-wire M^{3x} , lamp 16, switch 17, wire 83, circuit-closer 68^a, line-wire M^2 , coil 20^b of indicator B, through contacts e e^2 of switch E, and fuse 14 to the negative bus-bar of the 80 station. The lamp 16 will therefore be 85 lighted. The armature 24 of the indicator B still points to the indicating-letter "D" on the indicating-plate to indicate "danger," and the ammeter 13 indicates the amount of current consumed by the lamp 16, the lamp 71, however, being now extinguished. Should, however, any of the apparatus in connection with the line-wire M^2 or M^3 suddenly fail in its functions—for instance, should the lamp 16 burn out—the armature 24 of the 90 indicator B will take a perpendicular position and the hand of the ammeter 13 will rest at its zero-mark. In such exceptional cases the signal-operator will have the apparatus in such condition inspected and until 95 the fault is remedied he will throw the lever of the reversing-switch F back into its former position to close with contacts f^2 f^3 , thereby relighting lamp 71 in lantern 4, thus giving a warning signal to the approaching 100 train. Supposing now that the track I to be arranged for an arriving train from L, the signal-operator will first close the switch E in case the plant had been shut off from the current-supply source, whereupon the 105 ammeter 13 shows the amount of current taken by signal-lamp 16. The indicator B will then point to the index D to indicate "danger," and thus assures the operator that the 110 semaphore-arm 3 is in its horizontal or danger-indicating position and the colored-glass disk of the tail-plate 3 covers the lamp 16 to also indicate "danger." By thus closing the 115 switch 12 the magnetic field of the switch-setting apparatus G and the semaphore mechanism H will be excited—i. e., a flux of lines of force will take its way through the armatures 29 and 55^a in the direction of 27^b to 27^a and 53^b to 53^a. That the said circuit is 120 perfect and that the fields are excited is shown by the increased inflection of the ammeter 13, the hand of which should coincide with a distinctly-marked index upon its scale. By 125 throwing the lever of the reversing-switch F onto the metallic contacts f and f' the am- 130

meter 13 will indicate the current consumption of the whole plant. The pointer of the instrument should also cover an index-mark of the scale. The indexes of the ammeter 5 may be of any approved type or construction, as the same *per se* forms no part of my present invention. Owing to the reversed current of the armature-circuit, the coils 31^a 31^b of the switch-setting apparatus G will 10 render the outer ends of the armature 29 north poles, consequently moving the armature to the left to release the circuit-closer 47^b and close the circuit at circuit-closer 47^a to form a branch circuit from line-wire M³ to 15 knife-contact f⁴, switch-blade of switch F, contact f, indicator-coil 19^a, line-wire M⁴, circuit-closer 47^a, resistance 81, wire 81^a, field-coil 27^b, main return-wire M⁶, back to the current source. Under this arrangement the 20 magnetic field of the coil 19^a exceeds that of the coil 19^b, so that the armature 23 of the indicator A is pulled to the left, as shown in dotted lines in Fig. 15, so that its pointer 23 coincides with the indicating-letter "I" on the 25 dial and indicates that the rail-switch has opened track I for traffic, as required. At the instant that the coils of the armature 29 are energized a flux of line of force in the semaphore-armature 55^a is also produced by 30 the coil 55^b, and as this magnetic flux is across the armature-field in the direction x to y—*i. e.*, in the same direction as the flow of magnetism through the stationary coils 53^b 53^a—the armature will be turned clockwise until 35 the semaphore-blade reaches the position at 3^x (shown in Fig. 14) and the lever 55ⁱ releases the circuit-closer 68^a and closes the circuit at the circuit-closer 68^b, thereby closing the circuit through the lamp 16, snapping 40 switch 17, wire 83, circuit-closer 68^b, line-wire M', coil 20^a of the indicator B, and return-wire to the current source. The armature 24 will be pulled to the left, and its pointer 26 will then coincide with the indicating-letter "C" on its dial to indicate that 45 the semaphore has taken its proper safety position and a clear signal is sent out by the lamp 16 from the casing 9. When the switch F is again opened, the armature 23 of the indicator A swings back to its perpendicular position, the current-flow through the two armatures is broken off, and the lamp 71 extinguished, while lamp 16 is kept burning. The switch-setting apparatus and the 50 semaphore-operating mechanism H are locked to their present positions by the toggle-spring attachments before referred to. By means of the snap-switch 17 the signal-operator is further enabled to observe at his station 55 whether and at what time the lamp 16 is turned out of circuit and the resistance 18 substituted therefor, and vice versa, by simply observing the time when the indicator B shows this change, it being understood that 60 as the switch 17 cuts out lamp 16 and cuts in 65

resistance 18, and vice versa, the indicator B fluctuates, dropping to zero at the instant the change is made from lamp to resistance and moving to its indicating position immediately the resistance or the lamp is cut in. 70 The principal object of switch 12 is to open and close heating and field circuits for any period of time without causing changes in the signals.

From the foregoing, taken in connection 75 with the accompanying drawings, it is thought the complete construction, operation, and many advantages of my invention will be readily understood, and while I have particularly described my present invention 80 as being particularly adapted for use in connection with the improved system disclosed in my copending application before referred to, yet I desire it understood that my invention can be used in connection with other systems in which it would be applicable. 85

I do not desire to limit myself to the use of my present invention in connection with the particular system disclosed in my copending application before referred to. 90

Having thus described my invention, what I claim, and desire to secure by Letters Patent, is—

1. A switch-setting mechanism of the character stated, comprising a casing, a reciprocating electric motor mounted therein, a rod reciprocatably mounted in said casing and projecting outside thereof and adapted to be connected to the switch-point-connecting rod, a lever connection within the casing between the reciprocating motor and the reciprocating rod for imparting the motion of the motor to the rod, and circuit-closers mounted within the casing at each end of the motor and adapted to be operated by the reciprocating motor, substantially as shown and described. 95

2. In a switch-setting apparatus of the character stated, a casing, bearings detachably secured in the end walls therein, a rod reciprocatably mounted in said bearings and projecting outside of the casing, a coupling member on the end of said rod adapted to be connected with the switch-point-joining rod, a sleeve loosely held on the first-mentioned 100 rod, buffer-springs at each side of said sleeve on said first-mentioned rod, a reciprocating electric motor mounted within the casing, a lever pivotally secured within the casing and connected with said sleeve on said first-mentioned rod and with the reciprocating armature of the motor whereby the motion of the motor is imparted to said first-mentioned rod, said motor including stationary field-magnets and a reciprocating armature-magnet, a 105 shaft for said armature-magnet reciprocatably mounted in apertures in the field-magnets, and circuit-closers within the casing adapted to be engaged by said armature-shaft to operate the same as the shaft reaches 110

115

120

125

130

135

the limit of its movement in each direction, substantially as shown and described.

3. A switch-setting mechanism of the character stated, comprising in combination with an electric motor consisting of a pair of stationary magnet-coils, cup-shaped iron pole-pieces for receiving said magnet-coils, a pulley-shaped armature having cavities in its ends, armature-coils held in said armature-cavities, said cup-shaped pole-pieces being centrally apertured, a shaft endwise movably held in said apertures of the pole-pieces, said armature being fixedly secured to said shaft to reciprocate between the pole-pieces, and means for imparting the motion of the armature to switch-rail points substantially as shown and described.

4. A switch-setting mechanism of the character stated, in combination with an electric motor consisting of a pair of stationary magnet-coils, cup-shaped iron pole-pieces for receiving said magnet-coils, a pulley-shaped armature having cavities in its ends, armature-coils held in said armature-cavities, said cup-shaped pole-pieces being centrally apertured, a shaft endwise movably held in said apertures of the pole-pieces, said armature being fixedly secured to said shaft to reciprocate between the pole-pieces, a rod mounted for endwise movement and a lever joining said rod with said armature to impart the armature motion to the rod, said rod having means for connecting with the switch-rail-connecting rod.

5. A switch-setting mechanism of the character stated, comprising in combination with an electric motor consisting of a pair of stationary magnet-coils, cup-shaped pole-pieces for receiving said magnet-coils, a pulley-shaped armature having cavities in its ends, armature-coils held in said armature-cavities, said cup-shaped pole-pieces being centrally apertured, a shaft endwise movably held in said apertures of the pole-pieces, said armature being fixedly secured to said shaft to reciprocate between the pole-pieces, a rod mounted for endwise movement and a lever joining said rod with said armature to impart the armature motion to the rod, said rod having means for connecting with the switch-rail-connecting rod, circuit-closers mounted adjacent said pole-pieces and adapted to be engaged by the armature-shaft as it reaches the limit of its movement in each direction and toggle-spring devices for holding the parts in the position they assume when the armature is moved to the limit of its stroke in each direction, substantially as shown and described.

6. A switch-setting mechanism of the character stated, comprising the combination with an electric motor consisting of a pair of stationary magnet-coils, cup-shaped iron pole-pieces for receiving said magnet-coils, a pulley-shaped armature having cavities in

its ends, armature-coils held in said armature-cavities, said cup-shaped pole-pieces being centrally apertured, a shaft endwise movably held in said apertures of the pole-pieces, said armature being fixedly secured to said shaft to reciprocate between the pole-pieces, a rod mounted for endwise movement and a lever joining said rod with said armature to impart the armature motion to the rod, said rod having means for connecting it with the switch-rail-connecting rod, of circuit-closers mounted adjacent said pole-pieces and adapted to be engaged by the armature-shaft as it reaches the limit of its movement in each direction, toggle devices for holding the parts in the position they assume when the armature has moved to the limit of its stroke in each direction, and a hermetically-closed housing for the whole, substantially as shown and described.

7. In a switch-setting apparatus, an electric motor comprising a pair of stationary field-magnets each consisting of a cup-shaped iron pole-piece and energizing-coils held within the cup portion of said pole-pieces, a cylindrical tubular casing secured to said pole-pieces and closed at the ends by said pole-pieces, said casing consisting of non-magnetic material, means for securing the energizing-coils of the field-magnets in position thereon, a pulley-shaped armature having cup portions at each end and mounted for reciprocation between the said pole-pieces within the casing, a shaft passing through apertures in the pole-pieces upon which said armature is fixedly secured, energizing-coils secured within the cup-shaped portion of the armature, means for holding said last-named coils in position, a reciprocating rod mounted adjacent to said motor, elastic connections between said rod and said motor-armature, whereby the motion of the armature is imparted to the rod, means for holding the rod and armature to their moved positions, and a hermetically-closed housing for the whole, substantially as shown and described.

8. In a switch-setting apparatus, an electric motor comprising a pair of stationary field-magnets each consisting of a cup-shaped iron pole-piece and energizing-coils held within the cup portion of said pole-pieces, a cylindrical tubular casing secured to said pole-pieces and closed at the ends by said pole-pieces, said casing consisting of non-magnetic material, means for securing the energizing-coils of the field-magnets in position thereon, a pulley-shaped armature having cup portions at each end and mounted for reciprocation between the said pole-pieces within the casing, a shaft passing through apertures in the pole-pieces upon which said armature is fixedly secured, energizing-coils held within the cup-shaped portion of the armature, means for holding said last-named coils in position, a reciprocating rod mounted

adjacent to said motor, elastic connections between said rod and said motor-armature, whereby the motion of the armature is imparted to the rod, means for holding the rod and armature to their moved positions, a hermetically-closed housing for the whole, and circuit-closers mounted within said housing adjacent the ends of said motor and adapted to be engaged by the motor-shaft as it reaches the end of its stroke substantially as shown and described.

9. An apparatus of the character stated, comprising in combination with a pair of stationary field - magnets consisting of cup-shaped iron pole-pieces and energizing-coils held within the said pole-pieces, a housing of non-magnetic metal secured to and closed at the ends by said field-magnets, means for holding the coils of the field-magnets in position, said housing consisting of two semicylindrical parts embracing the pole-pieces to leave two longitudinal openings of equal widths extending the entire length of the housing and diametrically opposite to each other, said pole-pieces including centrally-apertured hubs to form bearings, a shaft longitudinally slideable in said hub-bearings, insulating-pins in the ends of said shaft, a pulley-shaped iron armature fixedly secured to the middle portion of said shaft, said armature having coil-receiving portions at each end, energizing-coils mounted in said armature, means for holding said coils in position on the armature, said armature including

35 a cylindrical rim having a pair of diametrically-disposed parallel grooves, a block of insulating material secured to the armature in one of said grooves and adapted to permit passage of the terminal wires of the armature-coils and to project through one of the openings between the housing portions, a metallic block secured to the armature in the other armature-groove, said block having a projecting stud and adapted to project 40 through the other opening between the housing-sections, one of said sections being formed with a lug, a lever pivotally secured to said lug and having a bifurcated end to engage the stud of the metallic armature-block and a 45 longitudinally-movable rod adapted to be engaged by the free end of said last-named lever for imparting motion to the switch-shifting rod, substantially as shown and described.

55 10. An apparatus of the character stated, comprising in combination with a pair of stationary field - magnets consisting of cup-shaped iron pole-pieces and energizing-coils held within the said pole-pieces, a housing of non-magnetic metal secured to and closed at the end by said field-magnets, means for holding the coils of the field-magnets in position said housing consisting of two semicylindrical parts embracing the pole - pieces to 60 leave two longitudinal openings of equal

widths extending the entire length of the housing and diametrically opposite to each other, said pole-pieces including centrally-apertured hubs to form bearings, a shaft longitudinally slideable in said hub-bearings, insulating-pins in the ends of said shaft, a pulley-shaped iron armature fixedly secured to the middle portion of said shaft, said armature having coil-receiving portions at each end, energizing-coils mounted in said armature, means for holding said coils in position on the armature, said armature including a cylindrical rim having a pair of diametrically-disposed parallel grooves, a block of insulating material secured to the armature in one of said grooves and adapted to permit passage of the terminal wires of the armature-coils and to project through one of the openings between the housing portions, a metallic block secured to the armature in the other armature-groove, said block having a projecting stud and adapted to project through the other opening between the housing-sections, one of said housing - sections being formed with a lug, a lever pivotally secured to said lug and having a bifurcated end to engage the stud of the metallic armature-block and a longitudinally-movable rod adapted to be engaged by the free end of said last-named lever for imparting motion to the switch, and 95 a pair of circuit-closers each adapted to be engaged by the armature-shaft as it reaches the limit of its stroke substantially as shown and described.

11. An apparatus of the character stated, comprising in combination with a pair of stationary field - magnets consisting of cup-shaped iron pole-pieces and energizing-coils held within the said pole-pieces, a housing of non-magnetic metal secured to and closed at the ends by said field-magnets, means for holding the coils of the field-magnets in position, said housing consisting of two semi-cylindrical parts embracing the pole-pieces to leave two longitudinal openings of equal widths extending the entire length of the housing and diametrically opposite to each other, said pole-pieces including centrally-apertured hubs to form bearings, a shaft longitudinally slideable in said hub-bearings, insulating-pins in the ends of said shaft, a pulley-shaped iron armature fixedly secured to the middle portion of said shaft, said armature having coil-receiving portions at each end, energizing-coils mounted in said armature, means for holding said coils in position on the armature, said armature including a cylindrical rim having a pair of diametrically-disposed parallel grooves, a block of insulating material secured to the armature in one of said grooves and adapted to permit passage of the terminal wires of the armature-coils and to project through one of the openings between the housing portions, a metallic block secured to the armature in the 120

125

130

other armature-groove and having a projecting stud adapted to project through the other opening between the housing-sections, one of said housing-sections being formed 5 with a lug, a lever pivotally secured to said lug and having a bifurcated end to engage the stud of the metallic armature-block and a longitudinally-movable rod adapted to be engaged by the free end of said last-named lever for imparting motion to the switch-shifting rod, and a pair of circuit-closers each adapted to be engaged by the armature-shaft as it reaches the limit of its stroke, and toggle-spring devices for securing the parts 10 in their extreme position, substantially as shown and described.

12. An apparatus of the character stated, comprising in combination with a pair of stationary field-magnets consisting of cup-shaped iron pole-pieces and energizing-coils held within the said pole-pieces, a housing of non-magnetic metal secured to and closed at the ends by said field-magnets, means for holding the coils of the field-magnets in position, said housing consisting of two semicylindrical parts embracing the pole-pieces to leave two longitudinal openings of equal widths extending the entire length of the housing and diametrically opposite to each 20 other, said pole-pieces including centrally-apertured hubs to form bearings, a shaft longitudinally slidable in said hub-bearings, insulating-pins in the ends of said shaft, a pulley-shaped iron armature fixedly secured to the middle portion of said shaft, said armature having coil-receiving portions at each end, energizing-coils mounted in said armature, means for holding said coils in position on the armature, said armature including a 25 cylindrical rim having a pair of diametrically-disposed parallel grooves, a block of insulating material secured to the armature in one of said grooves and adapted to permit passage of the terminal wires of the armature-coils and to project through one of the openings between the housing portions, a metallic block secured to the armature in the other armature-groove, said block having a projecting stud adapted to project through 30 the other opening between the housing-sections, one of said sections being made with a lug, a lever pivotally secured to said lug and having a bifurcated end to engage the stud of the metallic armature-block, a longitudinally-movable rod adapted to be engaged by the free end of said last-named lever for imparting motion to the switch-shifting rod, a pair of circuit-closers each adapted to be engaged by the armature-shaft as it reaches the 35 limit of its stroke, toggle-spring devices for securing the parts in their extreme positions, and a hermetically-sealed housing for the whole.

13. An apparatus of the character stated 40 comprising an electric motor consisting of a

pair of stationary field-magnets, each comprising a cup-shaped iron pole-piece, energizing-coils held within said cup-shaped pole-pieces, a pulley-shaped armature having cup-shaped ends, energizing-coils held within 45 said cup-shaped ends of the armature, an armature-shaft fixedly secured to the armature and reciprocatably mounted in bearing-apertures in the cup-shaped pole-pieces, said armature being adapted for reciprocatable motion between said cup-shaped pole-pieces, a switch-shifting rod, bearings for said rod, said switch-shifting rod being mounted parallel with the armature-shaft and adapted to be connected with the rail-switch-connecting 50 bar, a metallic sleeve slidable upon said switch-shifting rod, adjusting-nuts at each side of said metallic sleeve on said rod, coil-springs mounted on the rod between the sleeve and the adjusting-nuts, a pivotally-mounted lever having one end in connection with the armature and the other end in connection with the sleeve, and a toggle-spring attachment secured to said switch-shifting rod at one end, and fixedly held at its other end to 55 lock the parts to their shifted positions, substantially as shown and described.

14. An apparatus of the character stated, comprising an electric motor consisting of a pair of stationary field-magnets, each comprising a cup-shaped iron pole-piece, energizing-coils held within said cup-shaped pole-pieces, a pulley-shaped armature having cup-shaped ends, energizing-coils held within 60 said cup-shaped ends of the armature, an armature-shaft fixedly secured to the armature and reciprocatably mounted in bearing-apertures in the cup-shaped pole-pieces, said armature being adapted for reciprocatable motion between said cup-shaped pole-pieces, a switch-shifting rod, bearings for said rod, said switch-shifting rod being mounted parallel with the armature-shaft and adapted to be connected with the rail-switch-connecting 65 bar, a metallic sleeve slidable upon said switch-shifting rod, adjustable nuts at each side of said metallic sleeve on said rod, coil-springs mounted on the rod between the sleeve and the adjusting-nuts, a pivotally-mounted lever having one end in connection with the armature and the other end in connection with the sleeve, a toggle-spring attachment, said toggle-spring attachment comprising a swing-bracket mounted for oscillatory movement, an eyebolt longitudinally mounted in 70 said bracket, a collar fixedly secured to said eyebolt between the bearing portions of the bracket, a coil-spring on said eyebolt between said collar and one of said bracket-bearing portions, a clevis secured to the 75 switch-shifting rod, said eyebolt being pivotally connected with said clevis, said toggle attachment being arranged to hold the parts in their shifted positions, substantially as shown and described.

15. An apparatus of the character stated, comprising an electric motor consisting of a pair of stationary field-magnets, each comprising a cup-shaped iron pole-piece, energizing-coils held within said cup-shaped pole-pieces, a pulley-shaped armature having cup-shaped ends, energizing - coils held within said cup-shaped ends of the armature, an armature-shaft fixedly secured to the armature and reciprocably mounted in bearing - apertures in the cup-shaped pieces, said armature being adapted for reciprocatable motion between said cup - shaped pole - pieces, a switch-shifting rod, bearings for said rod, 10 said switch-shifting rod being mounted parallel with the armature-shaft and adapted to be connected with the rail-switch-connecting bar, a metallic sleeve slidable upon said shifting rod, adjustable nuts at each side of said 15 metallic sleeve on said rod, coil - springs mounted on the rod between the sleeve and the adjusting-nuts, a pivotally-mounted lever having one end in connection with the armature and the other end in connection 20 with the sleeve, a toggle-spring attachment, said toggle-spring attachment comprising a swing-bracket mounted for oscillatory movement, an eyebolt longitudinally mounted in said bracket, a collar fixedly secured to said 25 eyebolt between the bearing portions of the bracket, a coil-spring on said eyebolt between said collar and one of said bracket-bearing portions, a clevis secured to switch-shifting rod, said eyebolt being pivotally 30 connected with said clevis, said toggle-spring attachment being arranged to hold the parts in their shifted positions, circuit-closers operable by said armature-shaft and a hermetically-sealed housing for the whole substantially as shown and described. 35
16. In a switch-setting mechanism of the character stated, an electric motor comprising stationary field-magnets each consisting of a cup-shaped iron pole-piece, energizing-coils held within the cup shape pole-pieces, a pulley-shaped armature having cup-shaped coil-receiving portions at each end, energizing-coils held in said cup-shaped portions of the armature, an armature - shaft endwise 45 movable in apertures in the cup-shaped field-magnet pole-pieces and fixedly secured to the armature, said armature being adapted for reciprocating motion between the pole-pieces of the field-magnets, a switch-shifting rod, connections between 50 said switch-shifting rod and said motor-armature for imparting the motion of the motor-armature to the switch-shifting rod, circuit-closing devices mounted adjacent each end of the motor and adapted to be operated 55 by the armature-shaft as it reaches the limit of its stroke in either direction, each circuit-closer consisting of a base of insulating material, a metallic pillar having a horizontal arm or jib at its top end and being mounted 60 on said insulating-base, wire-receiving terminal screws at the foot of said pillar, a pin secured to the foot portion of said pillar, an adjustable set-screw in the outer end of said jib, an angular lever fulcrumed upon said pillar and provided with a pin on its operating-arm, a coil-spring connecting said last-named pin with said first-named pin, said armature-shaft having insulating members in its ends, an adjustable set-screw in the end piece of 65 one arm of each of said angle-levers of the circuit-closers for coöperating with said insulating-arm shaft members, means for securing said set-screw to its adjusted position, a metallic set-screw at the other end of the an- 70
- base, wire - receiving terminal screws at the foot of said pillar, a pin secured to the foot portion of said pillar, an adjustable set-screw in the outer end of said jib, an angular lever fulcrumed upon said pillar and provided with a pin on its operating-arm, a coil-spring connecting said first-named pin to said second-named pin said armature-shaft having insulating members in its ends, an adjustable set-screw in the end piece of the operating-arm of said angle-levers of the circuit-closers for operating with said insulating armature-shaft members, means for securing said set-screw to its adjusted position, a metallic set-screw at the other end of the angle-lever, 75 means for mechanically securing said last-named set-screw to its adjusted positions, a metallic cup being secured to said insulated base and out of contact with said pillar to co-operate with said last-named set-screw, said metallic cup adapted to contain mercury and to be mechanically engaged by said last-named set-screw when the circuit-closer has been operated upon by the armature-shaft, substantially as shown and described. 80
17. In a switch-setting mechanism of the character stated, an electric motor comprising stationary field-magnets each consisting of a cup-shaped iron pole-piece, energizing-coils held within the cup-shaped pole-pieces, 85 a pulley-shaped armature having cup-shaped coil-receiving portions at each end, energizing-coils held in said cup-shaped portions of the armature, an armature - shaft endwise movable in bearing - apertures in the cup-shaped field-magnet pole-pieces and fixedly secured to the armature, said armature being adapted for reciprocating motion between the pole-pieces of the field-magnets, a switch - shifting rod, connections between 90 said switch-shifting rod and said motor-armature for imparting the motion of the motor-armature to the switch-shifting rod, circuit-closing devices mounted adjacent each end of the motor and adapted to be operated 95 by the armature-shaft as it reaches the limit of its stroke in either direction, each circuit-closer consisting of a base of insulating material, a metallic pillar having a horizontal arm or jib at its top end and being mounted 100 on said insulating-base, wire-receiving terminal screws at the foot of said pillar, a pin secured to the foot portion of said pillar, an adjustable set-screw in the outer end of said jib, an angular lever fulcrumed upon said pillar and provided with a pin on its operating-arm, a coil-spring connecting said last-named pin with said first-named pin, said armature-shaft having insulating members in its ends, an adjustable set-screw in the end piece of 105 one arm of each of said angle-levers of the circuit-closers for coöperating with said insulating-arm shaft members, means for securing said set-screw to its adjusted position, a metallic set-screw at the other end of the an- 110

- 130

gle-levers, means for mechanically securing said last-named set-screw to its adjusted positions, a metallic cup being secured to said insulated base and out of contact with said 5 pillar to coöperate with said last-named set-screw, said metallic cup adapted to contain mercury and to be engaged by said last-named set-screw when the circuit-closer has been operated upon by the armature-shaft, 10 and a hermetically-sealed housing for the whole.

18. An apparatus of the character stated, comprising an electric motor consisting of field and armature magnets, said field-magnets each including a cup-shaped iron pole-piece, said armature consisting of a pulley-shaped body having oppositely-arranged cavities, energizing-coils held in said armature-cavities, energizing-coils held in the cup-shaped pole-pieces, a shaft to which said armature is fixedly secured and which projects through bearing-apertures in the pole-pieces to allow the armature to describe a longitudinal motion between the pole-pieces, a switch-shifting rod, lever connections between the switch-shifting rod and the armature to impart the motion of the armature to the switch-shifting rod, toggle-spring devices for locking the entire mechanism to its final positions, circuit-closers mounted adjacent the motor for operation by said motor-armature, an iron housing for hermetically and waterproofingly inclosing the entire electromechanical apparatus, said housing serving also 35 as a junction-box for all cable-joints, and comprising a metallic frame having a pair of oppositely-disposed outwardly-projected apertured bosses, metallic bearing-bushings secured to the said housing and projecting within said bosses, said bearings adapted to receive the switch-shifting rod, said housing having an inside flat portion, a terminal block having binding-screws, mounted on said flat portion within the housing, said 45 toggle devices being secured at one end to said housing, means carried by the housing for hermetically passing the leading-in cables through the housing-wall, a metallic bottom plate secured to the bottom of said 50 housing-frame and a removable cover-plate secured to the top of said housing-frame, said cover-plate having a plurality of finger-engaging eyebolts for the purposes specified.

19. In a switch-setting apparatus, an electric motor comprising a pair of stationary field-magnets each consisting of a cup-shaped iron pole-piece and energizing-coils held within the cup portion of said pole-pieces, a cylindrical tubular casing secured to said 60 pole-pieces and closed at the ends by said pole-pieces, said casing consisting of non-magnetic material, means for securing the energizing-coils of the field-magnets in position thereon, a pulley-shaped armature having cup portions at each end and mounted for

reciprocation between the said pole-pieces within the casing, a shaft passing through apertures in the pole-pieces upon which said armature is fixedly secured, energizing-coils secured within the cup-shaped portion of the 70 armature, means for holding said last-named coils in position.

20. In a system of the character stated, a source of electric energy, an electromagnetic switch-setting mechanism including field and armature coils in circuit with the source of electric energy, a reversing-switch for reversing the current in the armature, a balanced electromagnetic indicator in the armature-circuit, and means controlled by the switch-setting mechanism for varying the electric current as it passes through the indicator to upset its balance to indicate the position of the switch.

21. In a system of the character stated, a source of electric energy, an electromagnetic switch-setting mechanism including field and armature electromagnets, in circuit with the source of electric energy, a current-reversing switch in the armature-circuit, a balanced 90 electromagnetic indicator in the armature-circuit, and means controlled by the switch-setting mechanism for varying the electric current in a portion of the armature-circuit as it passes through the indicator to upset the indicator-balance to cause the indicator to indicate the position of the switch.

22. In a system of the character stated, a source of electric energy, an electromagnetic switch-setting mechanism including field and armature electromagnets, a pair of line-wires connecting the field-magnet coils with the source of electric energy, a second pair of line-wires connecting the armature-coils with the source of electric energy, a current-reversing switch in the armature-circuit, a balanced indicator including a pair of coils, one of which is connected in series with one armature line-wire and the other connected in series with the other armature line-wire, and means controlled by the switch-setting mechanism, for varying the current in one of said armature line-wires to upset the balance of the indicator to cause it to indicate the position of the switch-setting mechanism.

23. In a system of the character stated, a source of electric energy, an electromagnetic switch-setting mechanism including field and armature electromagnets, a pair of line-wires connecting the field-magnet coils with the source of energy, a second pair of line-wires connecting the armature-coils with the source of energy, a current-reversing switch in the armature-circuit, a balanced indicator including a pair of operating-coils, one of which is connected in series with one armature line-wire and the other connected in series with the other line-wire, and means controlled by the switch-setting mechanism for shunting a supplemental current through one of said ar- 130

mature line-wires to upset the balance of the indicator.

24. In a system of the character stated, a source of electric energy, an electromagnetic switch-setting mechanism including field and armature electromagnets, a pair of line-wires connecting the field-magnet coils with the source of electric energy, a second pair of line-wires connecting the armature-coils with the source of electric energy, a current-reversing switch in the armature-circuit, a balanced indicator including a pair of coils, one of which is connected in series with one armature line-wire and the other connected in series with the other armature line-wire, and means controlled by the switch-setting mechanism, for varying the current in one of said armature line-wires to upset the balance of the indicator to cause it to indicate the position of the switch-setting mechanism, without changing the flow of current through the armature.
25. In a system of the character stated, a source of electric energy, an electromagnetic switch-setting mechanism including field and armature electromagnets, a pair of line-wires connecting the field-magnet coils with the source of energy, a second pair of line-wires connecting the armature-coils with the source of energy, a current-reversing switch in the armature-circuit, a balanced indicator including a pair of operating-coils one of which is connected in series with one armature line-wire and the other connected in series with the other line-wire, and means controlled by the switch-setting mechanism for shunting a supplemental current through one of said armature line-wires to upset the balance of the indicator, without changing the flow of current through the armature.

26. In a system of the character stated, a source of electric energy, an electromagnetic switch-setting mechanism including field and armature electromagnets, a pair of line-wires connecting the field-magnet coils with the source of electric energy, a second pair of line-wires connecting the armature-coils with the source of electric energy, a current-reversing switch in the armature-circuit, a balanced indicator including a pair of coils, one of which is connected in series with one armature line-wire and the other connected in series with the other armature line-wire, and means controlled by the switch-setting mechanism, for varying the current in one of said armature line-wires to upset the balance of the indicator to cause it to indicate the position of the switch-setting mechanism, said last-named means comprising a circuit-closer closer connected to one armature line-wire and to the field-coil circuit midway between the field-coils, and a second circuit-closer likewise connected to the field-coil circuit and to the other armature line-wire, said circuit-closers each including portions to be engaged by the armature to operate the closers.
27. In a system of the character stated, a source of electric energy, an electromagnetic

switch-setting mechanism including field and armature electromagnets, a pair of line-wires connecting the field - magnet coils with the source of electric energy, a second pair of line - wires connecting the armature - coils with the source of electric energy, a current-reversing switch in the armature-circuit, a balanced indicator including a pair of coils, one of which is connected in series with one armature line-wire and the other connected in series with the other armature line-wire, and means controlled by the switch-setting mechanism, for varying the current in one of said armature line-wires to upset the balance of the indicator to cause it to indicate the position of the switch-setting mechanism, said last-named means comprising a circuit-closer connected to one armature line-wire and to the field-coil circuit midway between the field-coils, and a second circuit - closer likewise connected to the field-coil circuit and to the other armature line-wire.

28. In a system of the character stated, a source of electric energy, an electromagnetic switch-setting mechanism including field and armature electromagnets, a pair of line-wires connecting the field-magnet coils with the source of electric energy, a second pair of line-wires connecting the armature-coils with the source of electric energy, a current-reversing switch in the armature-circuit, a balanced indicator including a pair of coils, one of which is connected in series with one armature line-wire and the other connected in series with the other armature line-wire, and means controlled by the switch-setting mechanism for varying the current in one of said armature line-wires to upset the balance of the indicator to cause it to indicate the position of the switch-setting mechanism, said last-named means comprising a circuit-closer connected to one armature line-wire and to the field-coil circuit midway between the field-coils, and a second circuit-closer likewise connected to the field-coil circuit and to the other armature line-wire, said circuit-closers each including portions to be engaged by the armature to operate the closers.

29. In a system of the character stated, a source of electric energy, an electromagnetic switch-setting mechanism including field and armature electromagnets, a pair of line-wires connecting the field - magnet coils with the source of energy, a second pair of line-wires connecting the armature - coils with the source of energy, a current-reversing switch in the armature-circuit, a balanced indicator including a pair of operating-coils, one of which is connected in series with one armature line-wire and the other connected in series with the other armature line-wire, and means controlled by the switch - setting mechanism for shunting a supplemental current through one of said armature line-wires

- to upset the balance of the indicator, said means comprising a circuit-closer connected to one armature line-wire and to the field-coil circuit midway between the field-coils.
- 5 30. In a system of the character stated, a source of electric energy, an electromagnetic switch-setting mechanism including field and armature electromagnets, a pair of line-wires connecting the field-magnet coils with the 10 source of energy, a second pair of line-wires connecting the armature - coils with the source of energy, a current-reversing switch in the armature-circuit, a balanced indicator including a pair of operating-coils, one of 15 which is connected in series with one armature line-wire and the other connected in series with the other armature line-wire, and means controlled by the switch - setting mechanism for shunting a supplemental current through one of said armature line-wires to upset the balance of the indicator, said means comprising a circuit-closer connected to one armature line-wire and to the field-coil circuit midway between the field-coils, 20 and a second circuit-closer likewise connected to the field-coil circuit and to the other armature line-wire, said circuit-closers each including portions to be engaged by the armature to operate the closers.
- 25 31. In a system of the character stated, a source of electric energy, an electromagnetic switch-setting mechanism including field and armature electromagnets, a pair of line-wires connecting the field-magnet coils with the 30 source of energy, a second pair of line-wires connecting the armature-coils with the source of energy, a current-reversing switch in the armature - circuit, a balanced indicator including a pair of operating-coils one of which 35 is connected in series with one armature line-wire and the other connected in series with the other line-wire, means controlled by the switch-setting mechanism for shunting a supplemental current through one of said armature line-wires to upset the balance of the indicator, and electric heaters adapted to be 40 disposed adjacent the switch-rails and connected in series with the switch-setting mechanism.
- 45 32. In a system of the character stated, a source of electric energy, an electromagnetic switch-setting mechanism including field and armature coils in circuit with the source of 50 electric energy, a reversing-switch for reversing the current in the armature, a balanced electromagnetic indicator in the armature-circuit, and means controlled by the switch-setting mechanism for varying the electric current as it passes through the indicator to 55 upset its balance to indicate the position of the switch, and electric heaters adapted to be disposed adjacent the switch-rails and con-

nected in series with the switch-setting mechanism.

33. In a system of the character stated, a source of electric energy, an electromagnetic switch-setting mechanism including field and armature electromagnets, in circuit with the source of electric energy, a current-reversing switch in the armature - circuit, a balanced electromagnetic indicator in the armature-circuit, means controlled by the switch-setting mechanism for varying the electric current in a portion of the armature-circuit as it passes through the indicator to upset the indicator-balance to cause the indicator to indicate the position of the switch, and electric heaters adapted to be disposed adjacent the switch-rails and connected in series with the switch-setting mechanism.

34. In a system of the character stated, a source of electric energy, an electromagnetic switch-setting mechanism including field and armature electromagnets, a pair of line-wires connecting the field-magnet coils with the source of energy, a second pair of line-wires connecting the armature-coils with the source 90 of energy, a current-reversing switch in one armature - circuit, a balanced indicator including a pair of operating-coils, one of which is connected in series with one armature line-wire and the other connected in series with 95 the other line-wire, means controlled by the switch-setting mechanism for shunting a supplemental current through one of said armature line-wires to upset the balance of the indicator, and electric heaters adapted to be 100 disposed adjacent the switch-rails and connected in series with the switch-setting mechanism.

35. In a system of the character stated, a source of electric energy, an electromagnetic switch-setting mechanism including field and armature electromagnets, a pair of line-wires connecting the field-magnet coils with the source of electric energy, a second pair of line-wires connecting the armature-coils with the source of electric energy, a current-reversing switch in the armature-circuit, a balanced indicator including a pair of coils, one of which is connected in series with one armature line-wire and the other connected in series with the other armature line-wire, and means controlled by the switch-setting mechanism for varying the current in one of said armature line-wires to upset the balance of the indicator to cause it to indicate the position of the switch-setting mechanism without changing the flow of current through the armature, and electric heaters adapted to be disposed adjacent the switch-rails and connected in series with the switch-setting mechanism.
